UNITED STATES PATENT OFFICE.

BRIDGET L. BLANC, OF CHICAGO, ILLINOIS.

SHOE-TONGUE.

SPECIFICATION forming part of Letters Patent No. 623,350, dated April 18, 1899.

Application filed April 21, 1898. Serial No. 678,335. (No model.)

To all whom it may concern:

Be it known that I, BRIDGET L. BLANC, a resident of Chicago, in the county of Cook and State of Illinois, have invented certain new and useful Improvements in Shoe-Tongues, of which the following, when taken in connection with the drawings and reference-letters thereon, accompanying and forming a part hereof, is a full and complete description sufficient to enable those skilled in the art to which it pertains to understand, make, and use the same.

The object of this invention is to provide a shoe-tongue the use whereof will obviate pains and injuries to the instep of a person wearing a shoe having such shoe-tongue therein.

Briefly describing the same, this invention comprises a padded shoe-tongue, which may be secured in place by the shoe-lacing, not requiring to be stitched in place in the shoe with which it is used, which is not unsightly in appearance, and which will protect the foot from any injurious effect by the shoe-lacing, the tongue itself, or by the meeting edges of the shoe.

In the drawings referred to and wherein a letter of reference applied to a given part is used to designate such part throughout the several views, Figure 1 is a plan view of a tongue embodying the invention; Fig. 2, a vertical longitudinal section thereof on line 2-2 of Fig. 1 viewed in the direction indicated by the arrows, and Fig. 3 a front elevation of the upper part of a shoe having the tongue illustrated in Figs. 1 and 2 attached thereto.

For convenience of referring thereto the tongue is lettered X and the shoe Y.

A is a webbing forming one face of the tongue, and B a webbing forming the other face thereof.

C is the padding of the tongue, and consists, preferably, of horse-hair, cotton, wool, or other suitable material.

D D is stitching extending between webbing A and B and holding such webbing, together with the padding C, in proper relative position.

D' D' is a modified way of stitching the 50 webbing A and B and padding C together.

By the stitching indicated by letters D' D' there is no row of stitching crossing any other row of stitching, and I therefore deem such the better way of stitching the several parts 55 together.

E is binding extending around the tongue and secured thereto by the stitching E.

G is a shoe-lacing.

H H are holes in the tongue X, through 60 which the lacing G extends when the tongue is not stitched to a shoe, and I I are also holes through which such lacing extends.

J J are the lacing-holes of a shoe, such holes, as well as the lacing, forming, of course, 65 no part of my invention.

The padding C may be of substantially the same thickness throughout the tongue; but I prefer to have such padding thicker throughout the central body part of the tongue than 70 at the ends, as shown in Fig. 2, or sides, as in such case better protection is afforded the foot of the wearer and a more slighty appearance is given thereto.

I prefer to have the under webbing of the 75 tongue of woven fabric and the upper webbing A of thin leather.

When the tongue is used with a shoe to which it is not stitched, (such being the principal use thereof,) the shoe-lacing is put 80 through the holes H H and I I, as is well illustrated in Fig. 1, and such lacing is then put up through the lower two of the holes G, as is well shown in Fig. 3. When this is done, the tongue will remain in place, particularly 85 when the thickness thereof in the body part is greater than at the sides and ends when the lacing is laced thereover, and the tongue will protect the instep of the wearer from injury.

If desired, medication can be placed on the under side of the tongue to be absorbed, if in a liquid form, by the under webbing and by the padding.

Having thus described my invention, what 95 I claim, and desire to secure by Letters Patent, is—

A removable, padded shoe-tongue provided

with lacing-holes, in pairs, near the lower end thereof, in combination with a lacing extending over the top of the tongue, down through the lower holes of both pairs and up through 5 the remaining holes and through the lacing-holes of the shoe, whereby the portion of the lacing adjacent to the foot of the wearer is

embedded in the tongue; substantially as described.

BRIDGET L. BLANC.

In presence of—

FLORA L. BROWN,

FRANK B. MEECH.
